UNITED STATES PATENT OFFICE.

MARTIN RASMUSSEN, OF RACINE, WISCONSIN, ASSIGNOR TO EDWARD J. SCHOWALTER,
OF RACINE, WISCONSIN.

SPIKE.

1,022,261.

Specification of Letters Patent.

Patented Apr. 2, 1912.

Application filed April 18, 1910. Serial No. 556,230.

To all whom it may concern:

Be it known that I, MARTIN RASMUSSEN, (who has filed his intention to become a citizen of the United States,) residing at 5 Racine, in the county of Racine and State of Wisconsin, have invented certain new and useful Improvements in Spikes; and I do declare the following to be a full, clear, and exact description of the invention, such 10 as will enable others skilled in the art to which it appertains to make and use the same.

This invention relates to an improved spike.

15 The object of the invention is to provide a simply constructed and efficient toothed spike having means for gradually tightening it in the object into which it is driven and means for locking said tightening 20 means against withdrawal.

Another and important object of the invention is in the particular construction of the head of the spike whereby the same may be conveniently removed from the tie 25 or other object, when desired but cannot work out or become loosened in the latter when in use.

With the foregoing and other objects in view, the invention consists of certain novel 30 features of construction, combination and arrangement of parts, as will be more fully described and particularly pointed out in the appended claim.

In the accompanying drawings, Figure 1 35 represents a perspective view of one form of this improved spike with the key arranged in juxtaposition ready for insertion; Fig. 2 is a side elevation thereof; Fig. 3 is a view similar to Fig. 1 showing a slightly 40 modified form; Fig. 4 is a similar view of another form.

In the embodiment illustrated, in Fig. 1 a flat body member 1 is shown having a cleft 2 extending inwardly from its upper end 45 preferably to a point below its center to provide laterally spaced support engaging members 2^a and 2^b and one face of said cleft is smooth and the other face provided with downturned small ratchet teeth as 3 50 extending the greater portion of its length which are adapted to engage co-operating upwardly inclined teeth on a key to be described. This body member 1 is provided on its opposite edges with large upwardly 55 extending blade-like teeth as 4 designed for

engagement with the object into which it is to be driven such as a railroad tie or the like to prevent withdrawal of the spike.

A key 5 is adapted for insertion in the cleft 2 of the member 1 and has one flat 60 smooth face 6 for engagement with the smooth face of the cleft and with its other face tapering gradually toward its lower end and provided with a plurality of small upwardly inclined ratchet teeth as 7 adapted 65 to ride over the teeth 3 of the cleft wall when driven into the cleft and forces the members 2^a and 2^b gradually outward to cause a gradual tightening of the spike and hence avoid danger of splitting the tie or 70 other object into which the spike is driven. This spike is preferably provided with downwardly inclined bracing members 8 which may be omitted if desired.

As clearly shown in Fig. 1, the head of 75 the spike is composed of two outwardly projecting lugs 8' opposite the downwardly inclined brace members 8, the latter holding the said lugs a suitable distance above the upper surface of the tie or other object into 80 which the spike is driven, whereby after the key 5, has been driven into the spike and between the engaging members 2^a and 2^b a crowbar or other tool may be readily and conveniently inserted between said lugs for 85 spreading said members and thus releasing the key.

In the form shown in Fig. 3 a wood screw 9 is shown provided with a sharp point 10 and a cleft 11 similar to the cleft 2 of Figs. 90 1 and 2 and a similarly constructed key 12 is arranged for insertion in said cleft 11 and is preferably provided with a flat head 13 to facilitate its insertion.

In the form shown in Fig. 4 the spike 95 body 14 is preferably made round and provided with large teeth 15 on its outer face the cleft 16 being of similar construction to those shown in the other figures. The key 17 is similar to the other keys having an 100 eye 18 at its upper end to receive a ring 19 to adapt it for use as a hitching post.

From the foregoing description taken in connection with the accompanying drawings, the construction and operation of 105 the invention will be readily understood without requiring a more extended explanation.

Various changes in the form, proportion and the minor details of construction may 110

be resorted to without departing from the principle or sacrificing any of the advantages of the invention, as defined in the appended claim.

5 I claim as my invention:

A spike comprising the body portion with its central portion cut-away part way of its length to divide the spike, one of the inner faces of the divided parts being 10 smooth, and the other divided part having its inner face toothed, the outer faces of the divided parts having incuts arranged at intervals along its lengths, said incuts providing wedge shaped barbs having knife 15 edges, a wedge adapted to be wholly in-

serted between the divided portion having on one face teeth to engage the teeth of said divided part, and said wedge also having on its other side a smooth face to engage the smooth face of the divided part whereby 20 to force the knife edges of the wedge shaped barbs into an object.

In testimony whereof I have hereunto set my hand in presence of two subscribing witnesses.

MARTIN RASMUSSEN.

Witnesses:

GUY A. BENSON,
RICHARD G. HARVEY.
